(57) **CLAIM**

The ornamental design for a product merchandising shelf, as shown and described.

DESCRIPTION

FIG. 1 is a perspective view of a product merchandising shelf showing my new design.

FIG. 2 is a front elevational view thereof, the rear elevational view being a mirror image thereof.

FIG. 3 is a left side elevational view thereof.

FIG. 4 is a right side elevational view thereof.

FIG. 5 is a top plan view thereof.

FIG. 6 is a bottom plan view thereof; and,

FIG. 7 is a front elevational view thereof, shown with a plurality of the product merchandising shelves assembled in a vertical array, the rear elevational view being a mirror image thereof.

The broken lines showing product containers and an entire merchandising assembly are for illustrative purposes only and form no part of the claimed design.
